ACCORDIONS

Anthony De John, 1314 S. 13th St., Philadelphia 47, Pa.
Filed June 6, 1961, Ser. No. 115,121
5 Claims. (Cl. 84—376)

This invention relates to accordions and more particularly to an improved operating connection between the reed carrying heads of the accordion and supplemental to the bellows.

In the use of accordions, considerable difficulty arises because of the tendency for one head of the accordion, and usually the head in which the bass reeds are carried, to drop because of its weight.

It is the principal object of the present invention to provide an improved interconnection between the heads of an accordion and rearwardly disposed with respect to the bellows so as to avoid undesired interference with the bellows.

It is a further object of the present invention to provide an interconnection between the heads of an accordion having integral brackets which can be quickly and easily attached to accordions now in use, and by which the action of the accordion and the control thereof will be improved.

It is a further object of the present invention to provide an interconnection between the heads of an accordion having integral end brackets each of such can be readily attached to one of the heads, an expandable parallel motion connector therebetween and readily insertable rods for securing the connector at its ends to the end bracket.

It is a further object of the present invention to provide an interconnection between the heads of an accordion which is simple in construction, reliable in its action, which will be effective for maintaining the heads of the accordion for controlled movement with respect to each other and which will prevent excessive separation of the heads in use.

It is a further object of the present invention to provide an interconnection between the heads of an accordion for effecting a parallel motion actuation of the heads in use while permitting vertical swinging of the heads, and which is adapted for use with various sizes and models of accordions now in use.

It is a further object of the present invention to provide an interconnection between the heads of an accordion which is freely movable so as not to interfere with the free movement of the heads of the accordion.

It is a further object of the invention to provide an improved interconnection between the heads of an accordion which will support the accordion with the bellows in spaced relation to the body of the player and which is free from any tendency to catch on or grip the bellows, or the cushioning pad which is frequently interposed between one of the heads and the body of the player, or the clothing of the player.

It is a further object of the present invention to provide a simple form of interconnection between the heads of an accordion for maintaining a controlled relative movement thereof and which can be easily mounted in position by relatively inexperienced persons.

Other objects and advantageous features of the invention will be apparent from the description and claims.

The nature and characteristic features of the invention will be more readily understood from the following description, taken in connection with the accompanying drawings forming part thereof, in which:

FIGURE 1 is a rear elevational view of an accordion having the heads interconnected in accordance with the present invention and showing the heads in partially separated condition;

2

FIG. 2 is a rear elevational view similar to FIG. 1, showing the heads in closely spaced condition;

FIG. 3 is a top plan view of the accordion with the heads in the position shown in FIG. 1;

FIG. 4 is a fragmentary sectional view, enlarged, taken approximately on the line 4—4 of FIG. 1;

FIG. 5 is a fragmentary sectional view, enlarged, taken approximately on the line 5—5 of FIG. 2; and

FIG. 6 is a fragmentary sectional view taken approximately on the line 6—6 of FIG. 5.

10 It should, of course, be understood that the description and drawings herein are illustrative merely, and that various modifications and changes can be made in the structure disclosed without departing from the spirit of the invention.

15 Like numerals refer to like parts throughout the several views.

20 Referring now more particularly to the drawings, in which a preferred embodiment of the invention is illustrated, the heads of an accordion are shown at 10 and 11 with an interconnecting bellows 12 therebetween. The head 10 can have the treble and upper range reeds and their controls carried therein in the conventional manner, and the head 11 can have the bass reeds and their controls carried therein. The head 10 has a rear wall 14 and the head 11 has a rear wall 15.

25 A main bracket 20 is provided having a vertically extending bracket plate portion 21 and integral upper and lower mounting arms 22 and 23 shaped as illustrated particularly in FIGS. 3 and 5, to space the bracket plate portion 21 from the rear wall 14 of the head 10 and at an angle with respect thereto. The arms 21 and 22 are secured to the head 10 by a plurality of screws 24 at spaced locations and extending therethrough into the wall 14.

30 The bracket 20 has extending horizontally from the bracket plate portion 21, a pair of integral relatively closely spaced lugs 26 and 27, an intermediate integral lug 28 and a lower integral lug 29 for the reception of a vertical metallic support rod 30. The support rod 30 preferably has a head 31 with a knurled portion 32 for manual gripping if and when desired, and has a nut 33 on the threaded lower end portion 34 thereof (see FIG. 6). The nut 33 is also knurled as at 35 for facility of application.

35 The bracket 20 can be made of any desired material which is light in weight and strong, aluminum being particularly suitable.

40 An upper hinge plate 36 is provided and is freely rotatably mounted on the rod 30, between the lugs 26 and 27, and a lower hinge plate 37 is provided, also freely pivotably mounted on the rod 30. The upper hinge plate 36 is restrained against vertical movement by the lugs 26 and 27 while being swingable with respect to the rod 30. The lower hinge plate 37 is freely swingable on the rod 30 and is slidably movable vertically between the limit positions permitted by the lugs 28 and 29.

45 The hinge plates 36 and 37, as shown particularly in FIG. 6 for the hinge plate 37, are preferably provided with bearing sleeve inserts 40 of anti-friction material, such as Teflon, nylon or the like, which are not affected by damp weather or weather changes.

50 A second main bracket 45 is provided having a vertically extending bracket plate portion 46 and integral upper and lower mounting arms 47 and 48 extending from the plate portion 46 and shaped as illustrated particularly in FIGS. 1 to 4.

55 The bracket 45 is secured to the head 11 at spaced locations on the wall 15 by a plurality of screws 49 extending through the plate portion 46 and the arms 47 and 48.

The bracket 45 has extending horizontally from the plate portion 46 a pair of relatively closely spaced lugs 50 and 51, an intermediate integral lug 52 and a lower integral lug 53 for the reception of a metallic support rod. The support rod 54 preferably has a head 55 with a knurled portion 56 for manual gripping if and when desired, and has a nut 57 on the threaded lower end portion 58 thereof. The nut 57 is also knurled as at 59 for facility of application.

The bracket 45 can be made of any desired material but is preferably of the same material as the bracket 20. An upper hinge plate 60 is provided and is freely rotatably mounted on the rod 54, between the lugs 50 and 51, and a lower hinge plate 61 is provided, also freely pivotally mounted on the rod 54. The upper hinge plate 60 is restrained against vertical movement by the lugs 50 and 51 while being swingable on the rod 54. The lower hinge plate 61 is freely swingable on the rod 54 and slidably movable vertically between the limit positions permitted by the lugs 52 and 53.

The hinge plates 36 and 37 have bifurcated connecting portions 62 and 63 extending therefrom offset with respect to a vertical plane through the longitudinal axis of the rod 30 away from the rear wall 114 of the head 10.

The hinge plates 60 and 61 have bifurcated connecting portions 64 and 65 extending therefrom and offset with respect to a vertical plane through the longitudinal axis of the rod 54 forwardly towards the head 11. The upper hinge plate 60 is limited in its movement towards the head 11 by a stop post 66 carried by the bracket plate portion 46.

The bifurcated connecting portions 62 and 64 have downwardly extending meeting links 69 pivotally connected thereto by pivot pins 70 and the bifurcated connecting portions 63 and 65 have upwardly extending meeting links 71 pivotally connected thereto by pivot pins 72.

The links 69 are pivotally connected at their opposite ends by pivotal connections provided by pivot pins 73 in anti-friction bearings 74, and the links 71 are pivotally connected at their opposite ends by pivot pins 75 in anti-friction bearings 76. The links 69 and 71 at their intersections and intermediate their ends are connected by pivot pins 77 in anti-friction bearings 78. The connection of the links 69 and 71 at their ends to the rods 30 and 54 and intermediate their ends provides a parallel motion connection between the heads 10 and 11, with the upper hinge plates 36 and 60 restrained from vertical movement by their respective positioning between the lugs 26 and 27 and the lugs 50 and 51 with the lower hinge plates 37 and 61 free to slide on the rods 30 and 54 in the locations between the lugs 28 and 29 and the lugs 52 and 53. The hinge plates 36, 37, 60 and 61 and the links 69 and 71 preferably have their edges rounded or shaped to avoid any sharp configurations which would tend to catch on or abrade the clothing. The anti-friction bearings 74, 76 and 78 preferably are of synthetic plastic material, such as Teflon, nylon or the like, which is not affected by dampness nor by temperature changes.

The bracket 20 with its lugs 26, 27, 28 and 29 extends beyond the head 10 and in substantially complete overlapping relation to the bellows 12 in closed condition as will be seen in FIG. 2.

The position and character of mounting of the bracket 20 are such as to provide a support against the body of the user so that the bellows 12 is in spaced location away from the body in use while at the same time the tendency of the clothing of the user to become caught or abraded by the hinge plates 36, 37, 60 and 61 is avoided.

It will be noted that upon movement of the head 11 toward and away from the head 10 in playing the accordion and with swinging of the head 11 as desired with respect to the bellows 12 on the axis of the rod 54 and of the bellows 12 with respect to the head 11 on the axis

of the rod 30, the head 11 is supported from the head 10 by the connection provided exteriorly of the bellows so that little, if any, support of the head 11 by the hand of the player is required.

The head 11 may be freely and easily moved towards and away from the head 10 in the playing of the accordion, and is supported and maintained at the same level by the linkage provided on the rear of the accordion. The linkage is restrained from contact or engagement with the bellows in the more or less separated condition of the heads 10 and 11 by the engagement of the hinge plate with the stop post 66.

The freely movable pivotal mounting provided between the links 69 and 71, between the links 69 and 71 and the hinge plates 36, 37, 60 and 61 and between these hinge plates and the rods 30 and 54 provides a substantially friction free connecting and supporting structure so that no additional burden is placed on the player, the heads 10 and 11 being freely movable towards and away from each other, and swingable vertically but maintained in level condition. A very rapid or quivering effect can thus be easily obtained.

The brackets 20 and 45 may be readily applied to the heads 10 and 11 without involving any serious problems of alignment or adjustment.

This application is a continuation in part of my prior application Serial No. 780,726, filed December 16, 1958, now abandoned.

I claim:

1. In combination with a portable accordion having two reed carrying heads and an interposed bellows, one of said heads having the rear thereof for engagement with the body of the player during playing of the accordion and the other head being movable with respect to said one head, apparatus for controlling the relative movement of said other head with respect to said one head comprising a first vertically elongated unitary bracket member mounted on the rear of said one of said heads; said first bracket member having a plate portion disposed at an angle to the rear of said one of said heads to space the bellows from the body of the player, a second vertically elongated unitary bracket member mounted on the rear of said other of said heads, a vertical rod carried by each of said bracket members, and a plurality of pivotally connected links having portions pivotally connected to said rods and portions slidably and pivotally connected to said rods and providing a parallel motion connection between said heads retaining the heads at the same level and permitting relative movement of said heads toward and away from each other and swinging of said other head about the vertical pivotal axis provided by the vertical rod of its bracket member.

2. The combination defined in claim 1 in which said bracket member on said other head has a stop member thereon for limiting the movement of said links at that end thereof toward the bellows.

3. In combination with a portable accordion for support by the body of the user and having two reed carrying heads and an interposed bellows, one of said heads having the rear thereof for engagement with the body of the player during playing of the accordion and the other head being movable with respect to said one head, apparatus for controlling the relative movement of said other head with respect to said one head comprising a first vertical elongated bracket member having mounting portions mounted on the rear of said one of said heads and a vertical bracket plate integral therewith and extending therefrom at an angle with respect to the rear of said one head to maintain the bellows in spaced relation to the body of the player, said bracket plate having a pair of upper spaced horizontally disposed lugs, an intermediate horizontal lug and a lower horizontal lug, a second vertical elongated bracket member having a mounting plate mounted on the rear of the other of said heads, said bracket plate having a pair of upper spaced horizontally

disposed lugs, an intermediate horizontal lug and a lower horizontal lug, a vertical rod carried by each of said bracket members in intersecting relation to said lugs, upper hinge plates rotatably mounted on said rods between said upper lugs, lower hinge plates rotatably mounted on said rods and slidable between said intermediate lugs and said lower lugs, and a plurality of interconnected links pivotally connected to said hinge plates and providing a parallel motion connection between said hinge plates retaining said heads at the same level and permitting relative movement of said heads toward and away from each other and swinging of said other head about the vertical pivotal axis provided by the vertical pivotal axis provided by the vertical rod of its bracket member.

4. The combination defined in claim 3 in which said bracket member on said other head has a stop member thereon engageable by its contiguous hinge plate for limiting the movement of said hinge plate at that end toward the bellows.

5. In combination with a portable accordion for support by the body of the user and having two reed carrying heads and an interposed bellows, one of said heads having the rear thereof for engagement with the body of the player during playing of the accordion and the other head being movable with respect to said one head, apparatus for controlling the relative movement of said other head with respect to said one head comprising a first vertical elongated bracket member having mounting portions mounted on the rear of said one of said heads and a vertical bracket plate integral therewith and extending therefrom at an angle with respect to the rear of said head to maintain the bellows in spaced relation to the body of the player, said bracket plate having a pair of

upper spaced horizontally disposed lugs, an intermediate horizontal lug and a lower horizontal lug, a second vertical elongated bracket member having a mounting plate mounted on the rear of said other of said heads, said bracket plate having a pair of upper spaced horizontally disposed lugs, an intermediate horizontal lug and a lower horizontal lug, a vertical rod carried by each of said bracket members in intersecting relation to said lugs, upper hinge plates rotatably mounted on said rods between said upper lugs, lower hinge plates rotatably mounted on said rods and slidable between said intermediate lugs and said lower lugs, a pair of links pivotally connected to said upper hinge plates and pivotally connected at their lower ends, an additional pair of links pivotally connected to said lower hinge plates and pivotally connected at their upper ends, and additional pivotal connections for interconnecting intermediate portions of said first mentioned links and said additional links for providing a parallel motion connection between said hinge plates retaining said heads at the same level and permitting relative movement of said heads toward and away from each other and swinging of said other head about the vertical pivotal axis provided by the vertical rod of its bracket member.
